UNITED STATES PATENT OFFICE.

GEORGE A. RICHARDS AND ALFRED J. PRICE, OF WATERTOWN, WISCONSIN.

SOCKET-COVER FOR LIGHT-FIXTURES.

1,037,989.

Specification of Letters Patent. Patented Sept. 10, 1912.

Application filed February 8, 1912. Serial No. 676,234.

To all whom it may concern:

Be it known that we, GEORGE A. RICHARDS and ALFRED J. PRICE, both citizens of the United States, and residents of Watertown, 5 in the county of Jefferson and State of Wisconsin, have invented certain new and useful Improvements in Socket-Covers for Light-Fixtures; and we do hereby declare that the following is a full, clear, and exact 10 description thereof.

Our invention consists in what is herein particularly set forth with reference to the accompanying drawings and pointed out in the claims of this specification, its object being to provide simple, economical, practical, efficient, durable and attractive separable angular and preferably shade-holder covers for the bulb shank sockets of incandescent electric-light fixtures, each cover 15 having quick lock and release means for holding its sections in union. These means serve instead of the screws ordinarily employed for the same purpose and are easy of manipulation as well as time saving in practice, the points of pressure upon locking devices to effect a separation of sections of each socket-cover being preferably at diagonally opposite corners of the same.

Figure 1 represents a central vertical section view of a separable square socket-cover as aforesaid provided with means in accordance with our invention for holding its sections in union, the plane of the section cutting diagonal corners of the socket-cover 35 with which a fragment of a bulb-shade is similarly shown in the same figure. Fig. 2 of the drawings represents a side elevation of said socket-cover and fragment of bulb-shade therewith.

Referring by numerals to the drawings, 39 indicates the body-section and 4 the cap-section of a separable angular socket-cover of an incandescent electric-light fixture, such as a wall-bracket, ceiling-drop or chandelier. 45 Soldered or otherwise rigidly secured in diagonally opposite corners of the body-section of the socket-cover are ends of suitably bent spring-wires 5, their other ends 5' being free and extended through corner eyes

of said section of said cover. Bends 5" of 50 the wires, intermediate of their ends, extend through corner slots 6 of the body-section of the socket-cover, and the free ends of said wires are recessed, by pressure on said bends, to permit of the cap-section 4 of said cover 55 being slipped onto said body-section of the same. The cap-section of the socket-cover is provided with corner eyes that register with those of the body section, and the spring-wires being permitted to recoil their 60 free ends extend through the registering eyes of both cover-sections to latch said cap-section in readily detachable union with said body section of said cover.

It is preferable, as herein shown, to have 65 the free end 5' of each spring-wire latch 5 bent at an obtuse angle to the remainder thereof, whereby the cap-section of the socket-cover is caused to draw snug on the body section of the same, in engagement 70 therewith, when said latches recoil.

The body-section 3 of the socket-cover is shown provided with the usual screws 7 by which to hold a bulb-shade 8 in connection with said cover. 75

From the foregoing it is to be understood that our invention has no function as an incandescent electric-light socket, but only as a cover for such a socket, and the cover is preferably made to serve as a holder for a 80 shade for the bulb of an incandescent electric-light.

We claim:

1. A separable angular socket-cover of an incandescent electric light fixture having 85 the engaging ends of its body and cap sections provided with registering eyes, and spring-latches that being attached to one of said sections are engageable with said eyes of both and have the eye-engaging end of 90 each at an obtuse angle to the remainder thereof.

2. A separable angular socket-cover of an incandescent electric light fixture having the engaging ends of its body and cap sections provided with diagonally opposite 95 registering corner eyes, and spring-wires constituting latches secured in the eye-cor-

ners of the body-section of the cover, the wires being bent to extend through adjacent corner slots of said body section of said cover and having the eye-engaging end of each at an obtuse angle to the remainder thereof.

In testimony that we claim the foregoing we have hereunto set our hands at Water-

town in the county of Jefferson and State of Wisconsin in the presence of two witnesses.

GEORGE A. RICHARDS.
ALFRED J. PRICE.

Witnesses:

ANNE N. MURPHY,
AUGUST W. SCHWENKE.
